PROCESS FOR REDUCING A THREE-PHASE FLUID SYSTEM TO A TWO-PHASE SYSTEM

George C. Cavanagh, Fresno, Calif., assignor to Ranchers Cotton Oil, Fresno, Calif.

Application November 27, 1956, Serial No. 624,701

9 Claims. (Cl. 260—428)

The present invention relates to the art of oil refining and more particularly to a continuous process for reducing a three-phase fluid system of agglomerated solid constituents in a liquid, some of which solid constituents are heavier than the liquid and others of which are lighter than the liquid because of volatile material entrapped therein, to a two-phase system for subsequent gravitational separation. The instant invention resulted as a solution to the problem of reducing such a three-phase system to a two-phase system, in which the three-phase system consisted of a miscella of oil in a suitable solvent therefor, such as hexane, and which system contained agglomerations of soapstock, some of which agglomerations were rendered lighter than the miscella by the entrapment of solvent therein. The succeeding description of the continuous process for convenience makes reference to such utilization but it is to be borne in mind that the invention is not limited to this specific use, being applicable to any comparable operation. Further, in referring to three-phase systems it is the intent to include all multiple phase systems more than two-phase which may result by entrapment of volatile constituents in solid agglomerations.

This application is a continuation-in-part of my prior co-pending application Serial No. 366,458, filed July 7, 1953 entitled "Extraction and Refining of Glyceride Oils and Fats From Source Materials Thereof" issued April 16, 1957 as U. S. Patent No. 2,789,120.

One of the difficulties previously believed inherent in the miscella refining of oils and fats was the removal of soapstock from the miscella after the treatment of the oils or fats with an alkaline reagent for refining purposes. Normally soapstock itself is heavier than such miscellas of oils or fats and solvents. However, during the practice of miscella refining processes portions of the solvents become entrapped in the agglomerations of the soapstock as they are formed or during subsequent processing. The entrapped solvents impart buoyancy to some of the agglomerations while other agglomerations remain heavier than the miscella. This has resulted in the establishment of three-phase systems which have defied continuous gravitational or other separation until the present invention. Even when permitted to stand, the three-phase systems persist with agglomerations of soapstock settling to the bottom of the miscella and other agglomerations and entrapped solvent floating to the top. Actually, the separation has heretofore been only partially effected by efforts to compress or squeeze the entrapped solvents from the agglomerations of soapstock after straining the latter from the miscella. Unfortunately, the agglomerations are frequently quite small and almost impossible physically to separate from the miscella by such operations as straining. Obviously centrifuge operations have been entirely unsatisfactory, in many instances resulting in tight emulsions or permanent suspensions of the soapstock and the miscella.

The straining and squeezing procedure has been time

2

consuming, has resulted in such ineffectual solvent and soapstock removal that the resultant oils have been unacceptable for most purposes for which they are intended, and has been so wasteful and expensive as to render miscella refining processes virtually useless for commercial purposes.

Prior to the present invention, efforts to break three-phase systems of the character described to two-phase systems by heating and cooling have not been successful in commercial operations. The procedures have been subject to certain fatal difficulties which have heretofore been regarded as inherent and inescapable. When such miscellas containing the buoyant and the heavy agglomerations of soapstock are heated as much as desired, they must be confined to avoid waste of the volatile solvent and the problems of such confinement and mixing have previously precluded success. The mixing has required the extension through the walls of a confining vessel of an agitating mechanism of some type requiring packing thereabout. It has been virtually impossible to maintain the packing under the conditions of heat and pressure involved. Further, such batch operation has involved voluminous vessels in order to retain the three-phase systems therein for sufficient time to achieve the desired heating and cooling. The utilization of such vessels for batch treatment has proved impractical because of the inefficiencies inherent to such operations. The utilization of such vessels in continuous processes has not been practical because it is impossible to make certain that the last miscella delivered to the vessel is the last to leave the vessel and accurately regulated treatment of the miscella has been precluded. Additionally, in such vessel operation there is an increased tendency for soapstock to coalesce with the sides of the vessel serving as insulation and further aggravating the problems of heating and cooling which at best are not expeditiously performed in large vessels.

An object of the present invention is, therefore, to provide an improved continuous process for reducing three-phase fluid systems to two-phase systems.

Another object is to provide a process suitable to the continuous reduction of three-phase fluid systems to two-phase systems in which the three-phase systems consist of miscellas of oils in solvents containing agglomerations of soapstock, some of which agglomerations are heavier than the miscella and others of which are rendered lighter than the miscella because of solvent entrapped therein.

Another object is to render miscella oil refining processes commercially practical by the provision of an improved process for the removal of soapstock from the miscella.

Further objects are to provide a process of the character described which is economical to perform, avoids waste of the materials involved, permits recapture of substantially all of the solvent employed for re-use, is suitable for continuous practice, can be rapidly employed so as to permit integration into continuous miscella refineries without curtailing or impeding operations, and which is dependable in the results attained.

In the drawings:

Fig. 1 is a schematic diagram of a portion of a miscella oil refining system embodying the principles of the present invention.

Fig. 2 is a fragmentary longitudinal section of a conduit employed in the system of Fig. 1 showing baffles optionally utilized therein.

Fig. 3 is a schematic diagram of a portion of a miscella oil refining system somewhat more fragmentary than Fig. 1 and showing a second form of pump arrangement for recycling purposes.

Referring in greater particularity to the drawings: Similar elements are given similar identifying numerals as in the preceding application of which the instant application constitutes a continuation-in-part. Thus, 60 designates an homogenizer through which a miscella of oil being refined and hexane, or other suitable solvent for the oil, is recycled. The homogenizer agglomerates soapstock formed in the oil by treatment thereof with caustic soda or other alkaline material and achieves a suitable "break" in the few seconds the miscella is in the homogenizer. For purposes of this description, the homogenizer simply illustrates a source of a three-phase fluid system which it is desired to reduce to a two-phase system. In a commercial refinery practicing the invention, the three-phase system consists of:

(1) Miscella of cottonseed oil in hexane with the hexane being present in amounts of from 10% or less to 80% of the weight of the oil.

(2) Agglomerations of soapstock which are heavier than the miscella.

(3) Agglomerations of soapstock which are buoyant in the miscella because of hexane entrapped therein.

The homogenizer 60 is fed with the miscella through a feed line 61 connected to an inlet 62 of the homogenizer. The three-phase system is discharged from the homogenizer through a conduit 63 connected to a heat exchanger indicated generally at 70.

The heat exchanger has an economizer 69 to which the conduit 63 is directly connected, a heater 71 and cooler 72.

The economizer has a first coil 80, a hot coil 81, and a cold coil 82, so named for reasons which will subsequently become apparent. The coil 80 is connected to the conduit 63 and to the cold coil, as at 83. An outlet conduit 84 leads from the interconnection of the coil 80 and the cold coil 82 from the economizer 69. A recycling pump 85 is connected to the outlet conduit 84 and to the heater 71. A coil 90 is provided in the heater having one end connected to the recycling pump 85 and an opposite end connected to the hot coil 81 of the economizer 69. The hot coil 81 interconnects the heater coil 90 and the cooler 72.

A coil 95 located in the cooler 72 interconnects the hot coil 81 and an inlet end of the cold coil 82.

The structures of the economizer 69, heater 71, and cooler 72 may take any form suitable to the heating of the miscella in the heater, the cooling of the miscella in the cooler, and the warming of cold miscella and the cooling of hot miscella in the economizer. For example, each may consist of a tank 97, 98, and 99, respectively, having their respective coils located therein. The economizer 69 may contain water or any other suitable medium for transmitting heat between the coils 80, 81, and 82. The tank 98 of the heater 71 may be entirely closed and have steam from any suitable source, not shown, supplied thereto to heat the coil 90 and miscella. Similarly, the tank 99 of the cooler 72 may be a closed tank and cold water from any suitable source, not shown, may be directed through the tank to chill the coil 95 and miscella.

A discharge conduit 100 is connected to the cold coil 82 in the economizer 69 in spaced relation to the interconnection 83 and is extended from the economizer for connection to means, not shown, for gravitationally separating the two-phase system discharged therethrough. In commercial operations, a centrifuge is employed for such gravitational separating purposes but it will be quite apparent that any suitable means may be utilized.

The coils 90 and 95 preferably, but not necessarily, contain baffles 105 as shown in Fig. 2. The baffles are for the purpose of agitating the miscella as it is heated and cooled to facilitate agglomeration of soapstock in the heater 71 and further agglomeration and settling of soapstock in the cooler 72. For reasons which will subsequently be alluded to, satisfactory results can be ob-

tained without the baffles because of agitation of the miscella incident to the heating and cooling.

Operation

The three-phase fluid system is directed from the homogenizer 60 through the conduit 63 into the coil 80. In the coil 80, the temperature of the miscella is somewhat elevated so that the subsequent heating requires less energy. The miscella passes through the coil 80 and out the conduit 84 to the pump 85. The capacity of the pump is greater than the rate of flow of the three-phase system into the economizer 70 from the homogenizer 60.

The partially warmed three-phase system is forced by the pump through the coil 90 where the system is raised to a temperature sufficient to volatilize the solvent in the system. When hexane is employed as the solvent, the temperature is raised to the range of from approximately 140° F. to approximately 158° F.

As the three-phase system is heated, the hexane, or other solvent, at least partially volatilizes imparting vigorous agitation to the system in addition to the agitation caused by the flow over the baffles 105. The heat serves to soften soapstock in the system so that as the entrapped solvent volatilizes it is released by the soapstock in the miscella. The system is directed through the coil 90 at a rate of flow such that it is agitated and heated in the heater for a period of from five to ten minutes.

From the heater, the fluid system is directed into the hot coil 81 where its heat is dissipated in warming the coils 80 and 82. Thus, although the fluid system is at from 140° F. to 158° F. as it enters the economizer, it is substantially cooler, frequently from 115° F. to 120° F. when it leaves the economizer and flows into the cooler coil 95.

As the fluid system passes through the cooler coil it is reduced in temperature sufficiently to condense any volatilized solvent and sufficiently to solidify previously melted or softened soapstock. When hexane is employed, the temperature of the fluid system is reduced to a range of from approximately 80° F. to approximately 110° F.

From the cooler coil 95, the fluid system is directed to the cold coil 82 in the economizer 69 where it is heated in preparation for discharge through the conduit 100 or recycling through the heater and cooler.

It will be recalled that the capacity of the pump 85 is substantially greater than the flow rate of the fluid system into the economizer through the conduit 63. This is for the purpose of compelling recycling of the system through the heater and cooler where, in spaced relation along the described interconnected coils constituting a conduit through the heat exchanger 70, the fluid system is successively heated to a temperature sufficient to soften the soapstock and to volatilize the solvent while being stirred or agitated and subsequently cooled to a temperature sufficient to condense the volatilized solvent and to agglomerate the soapstock also while being stirred or agitated. Since the capacity of the pump is greater than the supply of the fluid system to the economizer, the pump serves to draw a portion of the fluid system from the cold coil 82. It will, therefore, be understood that the flow of fluid system to the economizer through the conduit 63 and the flow from the economizer through the conduit 100 are equal but that the flow through the pump 85, heater coil 90, hot coil 81, cooler coil 95, and cold coil 82 is at a substantially greater rate.

As described, the flow of the fluid system to the economizer and the flow from the economizer are continuous and equal. Also, the input pressure and output pressure are preferably equal as are the input temperature and output temperature. With this in mind, it will be appreciated that as the system is heated in the coil 90 and portions of the solvent volatilized, there is a substantial volumetric increase which results in vigorous acceleration and agitation of the system in the coil 90. Inversely, the cooling and condensing of the solvent in the coil 95

results in a corresponding volumetric decrease also productive of agitation as the system is decelerated. Inasmuch as the volumetric increase and decrease are equal if the input and output temperatures and pressures are equal, the system is readily balanced for operation.

In actual practice it is found that a three-phase system of the character described can be reduced to a two-phase system by a single passage through the heat exchanger described with the system requiring only five or ten minutes in the heater 71 and a like period in the cooler 72. The recycling is advisable in commercial installations in order absolutely to insure the elimination of all buoyant soapstock so that as the system is discharged through the conduit 100 it consists of the miscella and soapstock which is heavier than the miscella and readily removed therefrom by centrifugation. Not only does the practice of the present invention enable the continuous, economical and effective removal of the soapstock but it results in superior refined oil, the avoidance of solvent loss by entrapment in the soapstock, and the obtaining of a substantially solvent free soapstock as a by-product of the operation.

Second form

A second form of the present invention is shown in Fig. 3 which makes provision for independent re-cycling through a heater and a cooler. An economizer is shown at 169, a heater at 171 and a cooler at 172. As before, the economizer has a first coil 180, a hot coil 181 and a cold coil 182. The first coil 180 is fed with the three-phase system from the conduit 63 in the manner previously described for the coil 80 of the economizer 169. The heater 171 provides a coil 190 and the cooler 172 provides a coil 195. The first coil 180 is connected to the coil 195 which in turn is connected to the cold coil 182. The cold coil 182 is connected to the coil 190 of the heater which in turn is connected to the hot coil 181. The hot coil extends from the economizer at 196 for connection to a centrifuge, not shown, or other means for gravitationally separating the resultant two-phase system. As before, the economizer 169, heater 171, and cooler 172 may provide appropriate averaging, heating and cooling means such as tanks 97, 98 and 99, respectively, in which the coils are contained. The tank 97 preferably contains a heat transmitting fluid, the tank 98 is supplied with steam for heating purposes and the tank 99 is chilled by water or suitable refrigeration.

A pump 198 interconnects opposite ends of the coil 195 of the cooler 172. Similarly, a pump 199 interconnects opposite ends of the coil 190 in the heater 171. The pumps are for the purpose of recycling the miscella through the cooler and through the heater. In the first form of the invention, a pump, not shown, forces the miscella through the homogenizer 60 and the heat exchanger at a rate of approximately twenty gallons per minute in a commercial installation. The pump 85 has a capacity of approximately one hundred gallons per minute to achieve the desired re-cycling through the exchanger. In this form of the invention each of the pumps 198 and 199 preferably have a capacity of approximately one hundred gallons per minute as the flow through the entire system is approximately twenty gallons per minute. Thus, there is a vigorous re-cycling achieved in both the heater 171 and the cooler 172.

Actually, because of vigorous agitation incident to volatilization in the heater, the pump 199 is frequently not employed. However, there is a far greater tendency for soapstock to deposit in the cooler and the pump 198 is preferably always utilized during operation of the second form the invention now described.

Although the invention has been herein shown and described in what is conceived to be the most practical and preferred embodiments, it is recognized that departures may be made therefrom within the scope of the invention, which is not to be limited to the details

disclosed herein but is to be accorded the full scope of the claims so as to embrace any and all equivalent methods and processes.

Having described my invention, what I claim as new 5 and desire to secure by Letters Patent is:

1. A process for reducing a three-phase fluid system having agglomerated solid constituents in a liquid, some of which agglomerated solid constituents are heavier than the liquid and others of which are lighter than the liquid 10 because of buoyant volatile material entrapped therein comprising flowing the three-phase system through a closed conduit at a predetermined rate of flow, and successively heating and cooling the system in positions in spaced relation along the conduit whereby the system is 15 agitated by successive acceleration and deceleration from said predetermined rate of flow caused by volumetric changes of the system due to the temperature changes concurrently respectively with heating and expansion of the agglomerated solid constituents and entrapped buoyant 20 volatile material and cooling and contraction of said solid constituents and buoyant material.

2. A process for reducing a three-phase fluid system having agglomerations of solid constituents in a liquid, some of which agglomerations are heavier than the liquid 25 and others of which are lighter than the liquid because of volatile buoyant material entrapped therein comprising flowing the three-phase system through a closed conduit, and successively heating and cooling the system in positions in spaced relation along the conduit, the heating 30 being sufficient to raise the temperature of the system including the entrapped material above the temperature of the volatilization of said material and the cooling being sufficient to lower the temperature of the system below the condensation temperature of said material.

3. A process for reducing a three-phase fluid system having agglomerations of solid constituents in a liquid, some of which agglomerations are heavier than the liquid and others of which are lighter than the liquid because of volatile buoyant material entrapped therein comprising 40 flowing the system through a closed conduit at a predetermined rate of flow while repeatedly and in rapid succession heating the system to a temperature sufficient to volatilize the entrapped material and cooling the system to a temperature sufficient to condense said volatilized material whereby the system is agitated by acceleration from the predetermined flow rate concurrently with volatilization of said material by volumetric changes of the 45 system due to the heating and whereby the system is agitated by deceleration to said predetermined flow rate caused by volumetric changes of the system due to cooling, which said agitation and successive volatilization and condensation releases the buoyant material from the 50 agglomerations.

4. A process for reducing a three-phase fluid system 55 of a miscella of oil and solvent containing agglomerated soapstock heavier than the miscella and agglomerated soapstock lighter than the miscella because of solvent entrapped therein to a two-phase system comprising successively heating the system to a temperature sufficient to soften the soapstock and to volatilize solvent contained therein and cooling the system to a temperature sufficient to condense the volatilized solvent and to agglomerate the soapstock, said heating and cooling being performed with the system in continuous flow.

5. A process for reducing a three-phase fluid system 65 of a miscella of oil and solvent containing agglomerated soapstock which tends to settle in the miscella and agglomerated soapstock which tends to float in the miscella to a two-phase system preconditioned for gravitational separation comprising flowing the system through a closed conduit while repeatedly and in rapid succession heating the system to a temperature sufficient to volatilize fractions of the solvent and cooling the system to a temperature sufficient to condense the volatilized 70 fractions of the solvent.

6. A process for reducing a three-phase fluid system of a miscella of oil and solvent containing agglomerated soapstock heavier than the miscella and agglomerated soapstock lighter than the miscella because of solvent entrapped therein to a two-phase system preconditioned for gravitational separation comprising passing the fluid system through a closed conduit having an intake end and an outlet end at a predetermined rate of flow to and from the conduit, the fluid system having a predetermined temperature at the intake end, heating the fluid system at a position in spaced relation to the outlet end of the conduit, cooling the fluid system at a position between the heating position and the outlet end, said fluid system being heated above and cooled below the predetermined intake temperature substantially equal amounts so that the total volume of the fluid system between the intake and outlet ends remains substantially constant, and recirculating the fluid system from the outlet end of the conduit to the intake end thereof at a flow rate greater than the predetermined flow rate to and from the conduit whereby the recirculated portions of the fluid system are subjected to periodic heating and cooling actions.

7. A continuous process for reducing a three-phase fluid system of a miscella of oil and hexane containing agglomerations of soapstock, some of which agglomerations are heavier than the miscella and some of which are lighter than the miscella because of hexane entrapped therein comprising passing the system through a closed conduit having an intake end and an outlet end at a predetermined rate of flow to and from the conduit, heating the fluid system at a position in spaced relation to the outlet end of the conduit to a temperature above approximately 140° F. but below approximately 158° F. to volatilize the hexane in the agglomerations and to soften the soapstock, and cooling the system at a position between the heating position and the outlet end of the conduit to a temperature above approximately 80° F. and below approximately 115° F. to condense the hexane and further to agglomerate and to harden the soapstock.

8. A continuous process for reducing a three-phase fluid system of a miscella of oil and hexane containing agglomerations of soapstock, some of which agglomerations are heavier than the miscella and some of which are lighter than the miscella because of hexane entrapped therein comprising passing the system through a closed conduit having an intake end and an outlet end at a predetermined rate of flow to and from the conduit, heating the fluid system at a position in spaced relation to the outlet end of the conduit to a temperature above approximately 140° F. but below approximately 158° F. to volatilize the hexane in the agglomerations and to soften the soapstock, and cooling the system at a position between the heating position and the outlet end of the conduit to a temperature above approximately 80° F. and below approximately 115° F. to condense the hexane and further to agglomerate and to harden the soapstock.

tions are heavier than the miscella and some of which are lighter than the miscella because of hexane entrapped therein comprising passing the system through a closed conduit having an intake end and an outlet end at a predetermined rate of flow to and from the conduit, heating the fluid system at a position in spaced relation to the outlet end of the conduit to a temperature above approximately 140° F. but below approximately 158° F. to volatilize the hexane in the agglomerations and to soften the soapstock, cooling the system at a position between the heating position and the outlet end of the conduit to a temperature above approximately 80° F. and below approximately 115° F. to condense the hexane and further to agglomerate and to harden the soapstock, and recirculating the fluid system from the outlet end of the conduit to the intake end thereof at a flow rate greater than the predetermined flow rate to and from the conduit whereby the recirculated portions of the fluid system are subjected to periodic heating and cooling actions.

9. A continuous process for preconditioning a fluid mixture of a miscella of oil and hexane containing agglomerations of soapstock, some of which agglomerations are lighter than the miscella and some of which are lighter than the miscella because of hexane entrapped therein comprising passing the mixture through a closed conduit containing baffles while heating the fluid to a temperature of from approximately 140° F. to approximately 158° F. whereby the mixture is agitated by the baffles while being heated and is further agitated by volatilization of the hexane, and immediately thereafter passing the previously heated and agitated fluid through a closed conduit containing baffles which is continuous with the preceding conduit while cooling the fluid to a temperature from approximately 80° F. to approximately 110° F. whereby the fluid is agitated during cooling, is further agitated by the condensation of the hexane and a two-phase system is established.
